[57] **CLAIM**

The ornamental design for a combined pole and base stabilizing clamp, as shown and described.

DESCRIPTION

FIG. 1 is a perspective view of a combined pole and base stabilizing clamp, showing my new design, the broken line showing of a pole and base is for illustrative purposes only, and forms no part of the claimed design; FIG. 2 is an enlarged top plan view of one segment of the clamp, the other two segments being identical, shown broken away for ease of illustration; FIG. 3 is an enlarged left side elevational view of the segment as viewed in FIG. 2; and,

FIG. 4 is an enlarged exploded perspective view thereof.
